UNITED STATES PATENT OFFICE.

MOSES L. HAWKS, OF NEW YORK, N. Y.

SHARPENING DEVICE.

No. 918,544.

Specification of Letters Patent. Patented April 20, 1909.

Application filed August 25, 1908. Serial No. 450,192.

To all whom it may concern:

Be it known that I, MOSES L. HAWKS, a citizen of the United States, and residing at New York, in the county of New York and State of New York, have invented certain new and useful Improvements in Sharpening Devices, of which the following is a specification, such as will enable those skilled in the art to which it appertains to make and use the same.

This invention relates to sharpening devices, and the object thereof is to provide an improved device of this class designed for use in sharpening knives of various kinds and classes, also for sharpening scissors, cleavers and like devices, and which may also be used for sharpening skates; and with this and other objects in view the invention consists in a device of the class specified constructed as hereinafter described and claimed.

The invention is fully disclosed in the following specification, of which the accompanying drawing forms a part, in which the separate parts of my improvement are designated by suitable reference characters in each of the views, and in which:—

Figure 1 is a side view of my improved sharpening device, Fig. 2 a view similar to Fig. 1 but showing the opposite side and a slight modification, and showing one of the parts of Fig. 1 in a different position, Fig. 3 a transverse section on the line 3—3 of Fig. 1, Fig. 4 a side view of a cutter bar which forms a part of my improved sharpening device, Fig. 5 a view of the cutter bar shown in Fig. 4 and looking in the direction of the arrow x, and, Fig. 6 a section on the line 6—6 of Fig. 2.

My improved sharpening device involves the employment of two spring side arms a which are preferably inwardly curved as shown in Fig. 1, and which are set inwardly as shown at a² to form a handle member a³ composed of two parts a⁴ connected at one end by a loop a⁵, all of said parts being preferably composed of a spring metal rod bent first to form the loop a⁵, then the handle members a⁴ and then the spring arms a.

Mounted on the spring arms a is a plate b provided with keepers b² through which said spring arms pass, and said plate may be adjusted on said arms, if desired, into different positions, or said plate may be permanently secured to said arms.

The plate b is provided centrally with two transverse slots or openings b³ forming transverse strips b⁴, three of which are preferably

employed, and the central strip b⁴ is bent laterally in one direction and the other strips b⁴ laterally in the opposite direction to form keepers b⁵ as shown in Fig. 3, and these keepers b⁵ are adapted to receive a file or cutter bar c which is passed therethrough longitudinally of the plate b.

The file or cutter bar c is preferably triangular in form in cross section, and the keepers b⁵ are similarly formed, and the plate b is preferably bent laterally longitudinally and centrally thereof, and a wedge d is driven through the central keeper b⁵ of the plate b so as to bear on the bar c and securely hold it in place, and the object of bending the plate b laterally and longitudinally is to bring the wedge d outside of the plane of the keepers b⁵ so that said wedge may be conveniently driven into position or driven out of position.

The inner end of the plate b is provided with a longitudinal recess e, the side walls of which are curved to form segmental edges e² at the opposite sides of the inner end of the bar c, and the outer end of said plate is provided with a longitudinal recess f the corners of the walls of which are rounded to form segmental edges f² which are more abrupt in their curve than the edges e² of the recess e at the outer end of the bar c.

When the hereinbefore described parts are assembled as shown in the drawing the inner end of the plate b and the inner end e² of the plate c is used for sharpening knife blades of any kind or class, and the edges of the blades are inserted at x on either side of the bar c, and the blades are moved back and forth so that the edges of the bar c will form the desired edge on said blades.

The edges f² at the opposite or outer end of the plate b and the corresponding part of the bar c are used for the purpose of sharpening the blades of scissors, cleavers, choppers and like instruments, the operation being the same as that above described.

The outer end of the bar c is beveled as shown at c³ to form an edge c⁴, and by moving said bar into the position shown in Fig. 2 the runner of the skate may be inserted into the recess f and drawn across the end of the bar c and a proper edge may be formed on said runner as will be readily understood. If the face of the skate runner is plain the edge c⁴ will be plain or straight, but if said face is grooved or concave the edge c⁴ of the bar c may be similarly formed.

I also provide means whereby my im-

proved sharpening device may be used as a can opener, and in order to do this I place on the transverse part of the loop a^5 of the handle portion of the device a sleeve g having a laterally and outwardly curved prong g^2 ; and I also mount on the handle portion of the device or the parts a^4 thereof a slide h provided with a pointed or triangular blade h^2 which projects outwardly in the same direction as the prong g^2 ; and by inserting the prong g^2 through the center of the head of a can the slide h may be adjusted so that the blade h^2 may be passed through the outer edge portion of said head, and then by turning the device by grasping the arms a the head of the can may be easily cut out as will be readily understood.

My improved sharpening device is simple in construction, comparatively inexpensive and perfectly adapted to accomplish the various results for which it is intended; and changes in and modifications of the construction herein described may be made, within the scope of the appended claims, without departing from the spirit of my invention or sacrificing its advantages.

Having fully described my invention, what I claim as new and desire to secure by Letters Patent, is:—

1. A sharpening device comprising a handle portion provided with projecting arms,

a plate secured to said arms and provided centrally and longitudinally thereof with keepers which project in opposite directions, a file or cutter bar passed through said keepers, and means for securing it therein, said plate being provided at its opposite ends with longitudinal recesses forming curved edges, the curve of the edges at one end being more abrupt than those at the opposite end. 3

2. A sharpening device comprising a handle portion provided with projecting arms, a plate secured to said arms and provided at its opposite ends with longitudinal recesses, 45 said plate also provided centrally and longitudinally thereof with transversely arranged keepers which project outwardly in opposite directions, a cutter bar inserted into said keepers, and means for securing it therein, 50 said cutter bar being beveled at the end forming a cutting edge thereon adapted to sharpen the runners of ice skates.

In testimony that I claim the foregoing as my invention I have signed my name in presence of the subscribing witnesses this 22nd day of August, 1908.

MOSES L. HAWKS.
